(57) **CLAIM**

The ornamental design for a tire release bar, as shown and described.

DESCRIPTION

FIG. 1 is a top, front and right side perspective view of a tire release bar, showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 2;

FIG. 11 is an enlarged view of portion 11 in FIG. 7; and,

FIG. 12 is an enlarged view of portion 12 in FIG. 8.

The evenly broken lines show the features of the tire release bar that form no part of the claimed design. The unevenly broken lines illustrate the boundaries of the enlarged views that form no part of the claimed design.

1 Claim, 12 Drawing Sheets
